[57] CLAIM

The ornamental design for a jewelry hanger and organizer,
as shown and described.

DESCRIPTION

FIG. 1 is a top perspective view of a jewelry hanger and
organizer;

FIG. 2 is a front view showing my new design;

FIG. 3 is an end view showing my new design;

FIG. 4 is a top perspective view of a second embodiment of
a jewelry hanger and organizer;

FIG. 5 is a front view of FIG. 4; and,

FIG. 6 is an end view of FIG. 4.

The rear of the jewelry hanger and organizer is unornamented.
